CLAIM

The ornamental design for a shoe lace system, as shown and described.

DESCRIPTION

FIG. 1 is a top left side perspective view of a shoe lace system, embodying our new design;

FIG. 2 is top view of the shoe lace system of this invention; and,

FIG. 3 is a left side elevational view of the shoe lace system of this invention.

The shoe lace system for the other foot is the mirror image of the embodiment shown.

The broken lines immediately adjacent the shaded areas represent the bounds of the claimed design while all other broken lines are directed to environment and are for illustrative purposes only; the broken lines form no part of the claimed design.
